UNITED STATES PATENT OFFICE.

BERNHARD YOUNG, OF FRANKFORT-ON-THE-MAIN, GERMANY.

ROTARY RETORT.

Application filed July 20, 1925, Serial No. 44,884, and in Germany October 3, 1924.

This invention relates to an improved inclined and rotary retort such as is used in the distillation of coal or the like.

In known rotary retorts there exists the disadvantage that the cylindrical surface is utilized to a comparatively small extent for the direct transference of heat to the charge.

In order to increase the quantity of heat transmitted through the shell of the retort, 10 various devices have been proposed, the majority of the same being based on the principle of increasing the useful surface by means of ribs or ledges.

The object of the present invention is to 15 provide an improved form of inclined and rotary retort which overcomes the difficulty previously mentioned. This is achieved according to this invention by providing, around the inner cylindrical surface of the 20 retort, chambers which are formed by walls or partitions running longitudinally of the retort and by an inner shell, said chambers carrying the charge, which enters them longitudinally of the retort, around with 25 them during its rotation.

The chambers may be spaced from one another circumferentially, leaving intermediate gaps, or may be adjacent to one another, forming a closed ring. In the longitudinal direction the ring or sector shaped chambers are spaced from each other at intervals of such a size that sensitive distillation products are not left too long in the immediate proximity of the hot shell surface of the retort. The dimensions of the chambers are determined by the nature of the charge and by the amount of steam or gas evolved during distillation. For example the chambers might be 2 metres long 40 and the interval between them 1 metre long. The distillation gases escape into the intervals between the chambers and are then drawn, since they follow the path of least resistance, into the interior of the retort 45 and to the outlet pipe.

This improved retort has the advantages that, firstly, the heated retort surface is utilized to a considerably greater extent for direct heat transference, and secondly, the 50 heat radiated from the hot shell surface of the retort has a much greater effect on account of the smaller distance of the charge from said surface, the heat taking effect on the charge being inversely proportional to 55 the square of the distance.

In order that the invention may be more

readily understood, reference is made to the accompanying drawings illustrating an embodiment of the invention.

Referring to the drawings, Fig. 1 shows 60 a vertical section through the improved retort within its furnace.

Fig. 2 shows a cross sectional view of the same showing the circumferentially spaced chambers, while Fig. 3 shows a cross sectional 65 view of a modified retort with chambers adjacent to one another.

Fig. 4 is a perspective view, partly broken away of the structure Fig. 3;

Fig. 5 is a similar view of the structure 70 Figs. 1 and 2.

In the drawings *a* represents the chambers either with circumferential spaces *b* between them (Figs. 1 and 2) or with chambers adjacent to each other (Fig. 3). The 75 longitudinal intervals are shown at *c*.

In the two forms shown the retort is designated by *e* and within and spaced from the interior wall of the retort is the inner shell, the one *d* being peripherally discontinuous, there being longitudinal spaces *b* between the chambers *a*, and the inner shell *d'* being peripherally continuous, the chambers *a* being separated by radial partitions *f*. 80

In both cases the chambers are longitudinally discontinuous, being separated at their adjacent open ends as shown at *c*. 85

I claim:

1. An inclined, externally heated, rotary retort, having separate open-ended chambers along its length on its inner surface formed by walls or partitions running longitudinally of the retort and by an inner shell, the material passing through the retort between said shell and the retort wall, whereby undue agitation of the material is prevented and the material is maintained in contact with the retort wall. 90

2. An inclined rotary retort as claimed in claim 1, in which the chambers are spaced 95 from each other longitudinally.

3. An inclined rotary retort as claimed in claim 1, in which the chambers are spaced from each other circumferentially.

4. An inclined rotary retort as claimed in 105 claim 1 in which the chambers are spaced from each other both longitudinally and circumferentially.

In testimony that I claim the foregoing as my invention, I have signed my name this 110 2d day of July, 1925.

DR. BERNHARD YOUNG.
